John Sharp. Letters Patent Dated March 28th 1812.

The Schedule referred to in these Letters Patent and making part of the same containing a description in the words of the said John Sharp himself of his Improved Hand and Water Loom -

This Machine consists of four upright posts, two front, and two back, girls and two girls on each side connected with posts as in other looms.

The Lath is a frame whose construction is somewhat as follows unto the lathe, of a common fly shuttle loom, it moves on turn upon pivots or guides which are situated in the bottom side girls of the frame under the webb, so that the stay at the top will nearly coincide with the under side of the webb, when sprung. The bottom side girls of the frame elevate the ends of a shaft of a wheel which I shall call the Treadle wheel, the said wheel has in it a slot or a channel in which pins or coggs are fixed. There is a plain and slotted piece that extends from one side pin of the lathe to the other in which one end of a hook is confined that operates the Treadle wheel on the circumference of said wheel chains are placed for the purpose of shifting the treadle, the said chains are drawn whose length may be increased or decreased at pleasure helping the webb a greater or less distance, and can be so shifted upon the wheel that various figures may be woven, or almost any number of treadles operated. The Treadles are hung in a slot which is confined to the lower front girl of the frame, with their points extending to the wheel. The above mentioned hook catches up on the pins or coggs which are fixed in the wheel and remaining in number as of the chains, there is another hook or catch that prevents the action of the wheel while the web is sprung, one end of which is confined to the back girl of the frame the other end has just a notch and extends to the pins or coggs in the wheel, and is liberated by the first named hook as it passes back to gain another hold. There is another wire or prop which extends from the lower front girl of the frame just under the

handles to the pins or tags in the wheel to prevent the reaction of it. The cloth however is hung in the two front posts of the frame a little below the breast beam, and has upon one end of it a ratchet. There is a block which extends from the front post directly under the ratchet in whose center and a little inwards, through out of which passes a hand or postle, whose upper end extends to the back of the ratchet, and its lower end hangs by a pivot in a piece that projects from the side piece of the lathe, and nearly in a level with the pivot on which the lathe swings, and a proper distance from it, to give a motive sufficient to take up the cloth. There is in the other mortise a lever which I shall call a regulating lever being in its middle for the purpose of regulating the taking up of the cloth, the postle being fixed to take up the cloth too fast is liberated by a pin in the lower arm of the lever in consequence of its upper arm being moved by a screw in the side piece of the lathe where the cloth is beat beyond its limited position the upper arm of this lever is made fast to the lathe by a string by which it is returned to the lathe, passing back and letting the postle fall on the ratchet after it has been liberated.

That which throws the shuttle I shall call the shuttle vibrato it is affixed under the cloth in or near the ^{middle of the} breast beam swinging or moving upon the pivot or yoke and is constructed with a plate of metal in whose middle is a slit or mortise extending from one end past its pivot or yoke to the other, or its middle in which a rod or staple is received. There is confined to the said plate one end of an arm, the other end of which extends under the bottom of the lathe to its centre of motion and is there fastened to the shuttle drivers, or a rod on which they are confined. There is another rod or a piece of metal which I shall call the older slate end of which is a surface or block calculated to slide or move upon the aforesaid rod or staple, it or near each end of the said rod or staple is a notch in which the older catches to throw the shuttle, the other end of the said slate is confined to a pin under the

batten of the lathe. The said piece to which the said shuttle is confined is pliant and elastic & will render the first impulse not too abrupt on the shuttle. The construction of the shuttle shows two rods whose upper surface just above the under side of the shuttle the said drivers are connected by a rod which slides in a channel that is cut in the bottom of the lathe.

There is inserted into the cylinder or cylinders that depends the harness, one or more cords, the said cords are soars on whose out or inside are weights to assist in springing the webb, nor to strain the webb the webb is a line that passes round one end of the gear beam, which has upon it a long wheel, whose arms or channels, begin at the bigness of the beam and increase in circumference until they arrive at the bigness of the intended rolls of cloth, the lower loop of the said line sustains a weight which hangs upon a pulley sufficient to strain the webb, the said line is shifted from one of the said channels to the other as the shuttle picks up the beam.

To support against the blow of the lathe there is a lever which is haled out the friction lever, haled by a pivot to the side gate of the frame where the lever goes against the main beam, the other arm of which suspends a weight and extends beyond the pivot of the lathe and directly under the piece in which the pointer is hung, the said piece is hung for the purpose of pressing down the long arm of the lever causing a greater friction upon the beam when the lathe hails the cloth beyond its limited position when impelled by weight the lathe is vibrated by a crank which is situated in the two front posts of the frame, and is connected to the piece in which the said stock is confined that operates the middle wheel, there is a pulley which plays loosely upon one end of the shaft of said crank and has in one side of it a pin or cog which strikes the end of an arm or lever which is confined to the shaft of said crank by a Pivot. There is to the front post in range of the said pulley a lever hinged by its middle for the purpose of stepping the lever the lower arm of the last mentioned lever has upon it

... three square pieces on its end bent, the bend of which is sufficient when once it is moved to the point of the arm to cast it off the pins or coggs and stop the loom. There is in each shuttle box a knee for the purpose of stopping the loom whenever the shuttle lodges in the webb or misses the box, one arm of each knee extends into the shuttle boxes, and is nearly parallel with them.

There is in each shuttle box a knee for the purpose of stopping the loom when ever the shuttle lodges in the webb or misses the box, one arm of each knee extends into the shuttle boxes, and is nearly parallel with them.

The other arm of the said knees are connected by a rod, so that when one is moved by the shuttle the other will have the same operation.

The arm of one of the said knees is kept in range of the upper arm of the lever, which stops the loom by a light spring and would invariably strike and move it, which would liberate the arm from the pins or coggs, if it was not moved in consequence of the shuttle striking the other arm of them, as it passes into the boxes. The pinions of the said knees against the shuttle also prevents its revolving.
